2 SHEETS—SHEET 2.

UNITED STATES PATENT OFFICE.

OTIS M. CROSBY, OF LOVELAND, COLORADO.

AUTOMATIC TRAIN CONTROL.

1,321,984.

Specification of Letters Patent. Patented Nov. 18, 1919.

Application filed September 11, 1917. Serial No. 190,807.

To all whom it may concern:

Be it known that I, OTIS M. CROSBY, a citizen of the United States, residing at Loveland, in the county of Larimer and 5 State of Colorado, have invented certain new and useful Improvements in Automatic Train Controls, of which the following is a specification.

This invention relates to an automatic 10 train control, and has special reference to devices which are adapted to prevent collisions.

One object of this invention is the production of an electrically operated system which will automatically stop a train moving 15 in the same direction on the same track as a preceding train at such a distance as to prevent a rear end collision.

Another object of this invention is the production of an automatic train control, 20 which has the track provided with a number of blocks, thereby causing a train in one block to close a circuit for automatically stopping a following train in the rear block.

A still further object of this invention in 25 the production of an automatic train control wherein a block is normally opened so as to permit a train to pass in one direction without any hindrance, although this train will automatically close the circuit for stopping 30 an immediately following train.

Another object of this invention is the production of an automatic train control wherein an electrically operated means is provided upon the locomotive for automatically 35 stopping the train when a circuit in the block upon which the train is moving is closed.

One practical form of construction and assembly of the present invention will be 40 hereinafter described and is illustrated in the drawings, in which—

Figure 1 is a plan view of a portion of a road illustrating the various connections for forming the different circuits,

Fig. 2 is a vertical section through the 45 automatic switch housing,

Fig. 3 is a horizontal section taken on the line 3—3 of Fig. 2, looking in the direction of the arrows,

Fig. 4 is a horizontal section taken on 50 line 4—4 of Fig. 2 looking in the direction of the arrows,

Fig. 5 is a diagrammatic view of the mechanism carried by the locomotive, illustrating 55 the device by which the locomotive is automatically stopped.

Fig. 6 is an enlarged sectional view, partly in elevation, taken through the automatic steam valve,

Fig. 7 is an enlarged sectional view, partly 60 in elevation, of the valve connected to the air pipes.

Referring to the accompanying drawings by numerals, it will be seen that the main 65 rails 1 are suitably insulated from each other as at 2, thereby causing the road-bed to be divided into a plurality of blocks. Each block is similarly wired and for this reason it is thought that the disclosure wiring of one block will be sufficient for clearly 70 disclosing the proper wiring of all of the blocks of the road-way.

The electrical sources of supply as shown 75 at 3, which may be in the form of low voltage storage batteries, are connected by the conductors 4 to the rails 1, as clearly shown in Fig. 1.

The automatic switch comprises a housing 5, as shown in Figs. 1 to 4 inclusive. An inverted L-shaped frame 6 is fixedly 80 mounted upon the lower portion of the housing 5, within the interior of this housing. A magnet 7 is fixedly secured to the upper free end of the frame 6, and the conductor wires 8 are connected to the magnet 7 and 85 pass through openings 9 formed in the frame 6. These conductor wires 8 are also attached to the binding posts 10 carried within the housing 5, while the conductor wires 8 then pass through openings 11 90 formed in the housing 5 adjacent to the binding posts 10 so as to be connected to the rails 1, as shown in Fig. 1.

The lower portion of the frame 6 is bifurcated as shown at 12 and carries the pivot 95 pin 13. It will of course be understood that the frame 6 is formed of any suitable insulating material, such as of hard rubber or the like. The armature 14 has a sleeve 15 formed thereon and this sleeve 15 is carried 100 upon the pin 13 as shown in Fig. 2. In this way the armature 14 is pivotally supported. This armature 14 tapers toward its rear end although it is comparatively broad at its forward end as shown in Figs. 3 and 4. The 105 magnet 7 is provided with a fixed core 16 directly above the magnetic block 17 mounted upon the armature 14.

Owing to the fact that the source of electrical supply 3 will cause electrical energy 110 to pass to the rails 1, and this electrical energy passes over the conductor wires for en-

ergizing the magnet 7. As this magnet 7 is energized the magnetism will cause the armature 14 to be drawn upwardly, to normally assume the position as shown in one of the automatic switch housings in Fig. 1. When however, the rails in one of the blocks are connected together in the short circuit manner the electrical energy will be taken up so as to be prevented from passing over the conductor wires 8 with sufficient intensity to energize the magnet 7 of a particular block. Therefore as the magnet 7 is deenergized, the armature 14 will fall to its lowermost position, as shown in Fig. 2 to close another circuit to be hereinafter disclosed.

It will be noted that binding posts 18 are also mounted within the housing 5 directly beneath the armature 14, while the conductor wires 19 are connected with the binding posts 18 and are also connected to the rails 1. A suitable source of high voltage electrical supply indicated at 20 is connected to one of the conductors 19 for forming an operating circuit for automatically controlling a train as hereinafter specified. Since the armature 17 is normally in its elevated position this circuit will not be closed but as soon as the armature 17 moves to its lowered position it will allow the operating circuit to be closed by the mechanism carried by the engine.

The locomotive 21, which for the purpose of illustrating the operation of the present invention, is shown diagrammatically in Fig. 5, is provided with an automatic control mounted thereon. This locomotive 21 is also provided with contact wheels 22 adjacent its front end, and it should be understood that these wheels should be suitably insulated from each other and also from the locomotive 21. The steam pipe 23 which leads from the usual steam dome, is provided with a valve casing 24, while the usual pipe 23' leads from the valve casing 24 in order to operate the steam throttle in the usual manner when the passage way through the pipes 23 and 23' is open. The plunger 25 is reciprocally mounted upon the valve casing 24 and this plunger 25 is provided with an opening 26 leading therethrough, as shown in Fig. 6. It should be understood that this plunger 25 is normally retained in an elevated position adjacent the upper portion of the valve casing 24, thereby causing an unobstructed passage to allow the steam to pass through the casing when the locomotive is being operated under normal conditions. The stem 27 is connected to the plunger 25 and projects from the lower portion of the valve casing 24 while the packing cap 28 is provided for preventing the accidental escaping of steam around the stem 27. The solenoid 29 is carried directly beneath the valve casing 24 and is electrically operated, as will be hereinafter specified. The core 30

of the solenoid 29 is connected to the stem 27 as shown in Figs. 5 and 6.

The air pipe 31 is provided with a T joint 32 and this pipe 31 extends beyond the T joint as shown at 31' to be connected to the control valve 53 operated by a handle 54. A pipe 55 leads beyond the valve 53 and for this reason it is obvious that when the engineer shifts the handle 54 passage through the valve 53 may be permitted so that air may pass through pipe 55 to the usual brake mechanism. After the brakes have been applied the handle 54 may be further shifted to allow the passage through nipple 56 to be unobstructed, thus permitting the air line to be bled. A short pipe 33 extends from the T joint 32 and is connected to the air valve casing 34, while the short pipe 35 extends from the air valve casing 34 and is connected to the T joint 36. A pipe 36' extends from the T joint 36 for conducting air to operate the usual air brake mechanism of the locomotive and train. The plunger 38 is reciprocally mounted within the air valve casing 34 and has a stem 39 leading therefrom, as shown in Fig. 7. The usual packing cap 40 is carried by the casing 34 for preventing the escaping of air around the stem 39. The solenoid 41 is carried in alignment with the air valve casing 34 and has its core 42 pivotally connected to the stem 39 as shown at 43. It should be noted that the plunger 38 is normally carried so as to abut against the filler block 44 at one end of the air valve casing 34, thereby preventing the passage of air through the pipe 33 and 35.

A brush 45 is carried by the forward portions of the locomotive 21 and is adapted to be electrically connected to one of the contact wheels 22. The conductor 46 leads from the brush 45 and is connected to the solenoid 41. A conductor 47 leads from the solenoid 41 and is connected to the solenoid 29, as shown in Fig. 5. A conductor 48 leads from the solenoid 29 and is connected to a second brush 49 carried by the forward portion of the locomotive 21, so as to engage the remaining contact wheel 22 upon the opposite side of the locomotive and engaging the opposite rail.

It should further be noted that a conductor 50 leads from the conductor 46 and is connected to a bell or other suitable signal 51, while the conductor 52 leads from the bell and is connected to the conductor 48, thereby forming a shunt circuit.

As above specified it should be understood that the plunger 25 is normally carried so as to permit a free passage of air or steam through the pipes 23 and 23', to be controlled by the usual steam throttle in a locomotive. It should also be understood that the plunger 38 normally closes the passage-way through the pipes 33 and 35, for causing the usual air-brake mechanism of the

locomotive and train to be operated in the usual manner and without interference from the automatic control.

When a train is passing in one direction, for instance to the left in Fig. 1, the usual wheels will cause the blocks upon which the train is passing to short circuit the source of supply from 3, thereby causing the magnets in the next block in the rear 10 to be deenergized, thereby allowing the armature to fall into engagement with the contact posts 18. As a consequence if a train is following and passing toward the left in Fig. 1 onto the block controlled by 15 the armature, the electrical current from the high voltage source of supply 20 will then pass over the conductor wires 19 to the rails 1, since the armature will form a closure between the contact posts 18. The 20 contact wheels of the second locomotive passing toward the left will pick up the current and the current from the source of energy 20 will then pass over the conductor 46 so as to energize the solenoid 41. 25 The current will then pass over the conductor 47 to energize the solenoid 29 and then from this solenoid 29 the current will pass over the conductor 48 to the remaining brush 49 and from this remaining brush 30 over the remaining contact wheel 22 to the remaining rail, thus forming a complete circuit. As the solenoids are instantaneously energized by the high voltage current, it is obvious they will draw their 35 cores inwardly so as to draw upon the plungers 25 and 38. As the plunger 38 is drawn so as to permit a free passage of air through the pipes 33 and 35 it is obvious that the brakes of the train will be automatically 40 set. As the plunger 25 is moved downwardly it will cause the opening 26 formed thereto to move out of registry with the pipes 23 and 23', thereby cutting off the supply of steam which drives the locomotive. 45 Thus as the motive power is cut off and the brakes are automatically set the locomotive will be stopped. It should also be noted that as the circuit is passing over the mechanism mounted upon the locomotive, it will also pass over the conductors 50 and 52, causing the signal 51 to operate. Therefore if for some reason the stopping mechanism fails to operate, the signal 51 within the cab will be sounded thus signaling 55 to the engineer so as to permit the engineer to bring the locomotive to a standstill.

From the foregoing description it will be seen that a very efficient automatic train control has been produced, so that the train passing upon an open block will not be stopped. If however, the roadway is provided with a train moving in the same direction the first train will cause the automatic switch in the rear block to be operated

for forming a new circuit, thereby causing the automatic control of an engine following in the same direction, to be actuated for automatically bringing the locomotive to a stand-still. It should be further understood that the system herein described is used to prevent rear end collisions, or to prevent a train passing in one direction from running into a block from which one rail has been displaced as the case of a wash-out or the like, thus preventing such train from running from the track. The system is intended to be used upon a roadway where all the traffic is passing in one direction and where the ordinary double track system is employed, it is necessary to provide a separate system as herein described for each track. It should be further understood that the source of supply 3 may be of a low voltage such for instance 85 as one or two low voltage storage batteries or cells which are only sufficiently strong enough to retain the armature of an automatic switch in an elevated position, but which current is not strong enough to actuate the solenoids carried by the engine. However, the source of supply 20 is of a very high voltage nature and for this reason the solenoids of the engine will be instantaneously energized to draw the cores 90 inwardly and thus cause the valves to be operated for cutting off the supply of steam normally controlled by the throttle and also applying the air brakes.

It is obvious that many minor changes 100 may be made in the construction of this invention, without departing from the spirit of the device, and for this reason it is not intended to limit the construction of the device to the specific form herein disclosed, since it is intended to include 105 all forms of the invention as fall within the scope of the device as claimed.

In which I claim:

1. In a system of the class described, the 110 combination of a plurality of blocks, an automatic switch for each block, a low voltage source of supply connected to each block and to the automatic switch of an adjacent block for normally rendering the 115 automatic switch inoperative the high voltage source of supply connected to each block and to said corresponding automatic switch, whereby when the low voltage current of an adjacent block is short circuited the automatic switch will become operative and close the circuit of the high voltage source of supply.

2. In a system of the class described, the 120 combination of a plurality of blocks, a source of low voltage electrically connected to each block, an automatic switch provided 125 for each block including an electromagnet and an armature and contact posts in the path of movement of said armature, con-

ductors connected to one block and also connected to the electromagnet of the switch of an adjacent block, whereby said armature will be normally retained in a set position by the magnet, a source of high voltage or electrical energy connected to each block and to the contact posts of the switch and said magnet being deenergized when the low voltage energy of the adjacent block 10 is short circuited, thus causing the arma-

ture to engage said contact posts for closing the high voltage circuit in the block of the switch.

In testimony whereof I affix my signature in presence of two witnesses.

OTIS M. CROSBY.
